UNITED STATES PATENT OFFICE

JAMES M. NAHON, OF MADRID, SPAIN

NONSKID DEVICE FOR BOOTS AND SHOES

Application filed August 1, 1930, Serial No. 472,248, and in Spain January 17, 1930.

The present invention is an improvement over my invention forming the subject matter of my co-pending application Serial No. 273,115, filed April 26, 1928, and comprises 55 a new device for fitting non-slip or anti-skid chains to boots and shoes.

In devices hitherto known for fixing the actual non-slip member to the boot or shoe, the disadvantage is present in that another 10 fixed or removable member is required, which is applied to the surface or side of the boot or shoe. This may cause discomfort to the foot of the wearer or cause one foot to strike against the other, whereby the 15 boot or shoe suffers in appearance and may even become damaged. Such systems also do not provide the necessary rigidity or secure fastening to the foot, and they move from place to place when the person walks. 20 It also happens that the chain, which, in order to be absolutely effective, should be taut or under tension, which can only take place in a limited number of positions, if at all; and, when loose, it is attended by the 25 following disadvantages among others:

The device becomes decentralized, whereby the non-slip effect is lost; a noise is produced when walking; and the foot may catch in any obstacle.

Finally, the chain often forms an obstacle and a source of discomfort beneath the sole of the shoe if the sole is not made of rubber or some other soft material when walking over hard surfaces, such as ice.

The present invention overcomes the disadvantages and defects pointed out in the foregoing and consists essentially in the arrangement of a number of supporting or securing members securely fixed between the 35 sole of the shoe and the upper part thereof or on the upper border of the sole itself. The supporting members may also be secured under the sole of the shoe, as, for example, in the arch part of the shoe near the heel. The supporting members are 40 adapted to secure one or more rows of chains, which are suitably arranged under the sole and also the heel, if desired. The supporting or securing members may, of 45 course, be hidden so that when the non-skid 50

or non-slip device is not in use it cannot be detected that the shoe is fitted with means whereby chains may be secured to the sole of the shoe; also, the supporting members are so provided that the chains may be fitted 55 or removed in a very short time by means of suitable clasps or hooks.

The non-slip or skid chains are maintained under tension when provided on the sole of a shoe by means of one or more 60 springs of any suitable type and also any discomfort to the foot from the chain may be rectified by interposing therebetween and the sole a strip of any soft material, preferably rubber.

It is a further object of the present invention to provide a cross-brace arranged between the inner sole and the outer sole of the shoe, which is adapted to interconnect the supporting members arranged on opposite sides of the shoe. This further strengthens and secures the supporting members to the shoe and also adds to the strength of the sole of the shoe by rendering it more 70 rigid. The cross-brace also prevents, to a 75 certain extent, any tendency of the sole to become deformed due to expansion or from any other cause which can readily happen with crepe rubber or other soles.

Further objects will be apparent from the 80 following description taken in connection with the accompanying drawings in which like characters indicate corresponding parts throughout and in which:

Figure 1 is a perspective view of a shoe 85 showing the bottom thereof and a portion of the sole pulled away to show the supporting members and the cross-brace.

Fig. 2 is a bottom view of the shoe of Fig. 1 with the non-skid chains fastened in 90 place,

Fig. 3 is a side view of the securing clasp in open position,

Fig. 4 is a top view showing the chains of Fig. 2 in a specific arrangement,

Fig. 5 is a side view of the shoe showing the supporting members, and

Fig. 6 is a side view similar to Fig. 5 but showing the chains secured to the supporting members.

In a preferred construction of the present invention, as clearly shown in Fig. 1, a pair of supporting or securing members *a*, preferably made of metal, are secured to the inner sole of the shoe so that the ends thereof project a trifle as indicated in Figs. 5 and 6. These supporting members are provided with a brace *b*, which is provided entirely within the construction of the shoe and, it, therefore, is invisible from the outside. The brace interconnects the supporting members together and thereby strengthens them and also the shoe itself in order to form a rigid construction. It is, of course, possible to secure these members in the shoe even after it has been completed, but it is preferable to supply them in the shoe at the time that it is manufactured.

The chains may be arranged in any suitable manner and any number can be utilized as may be desired, but for all practical purposes the construction shown in Fig. 2 has been found to be most adaptable for almost all conditions. The chain consists of three sections, of which the lateral sections *e'* are secured each by means of one end to a supporting member by means of link *e* shown in Fig. 6. The two chains are connected together at the other ends by a clasp *d* arranged approximately in the center of the sole on the bottom thereof, which acts at the same time as a spring and serves to impart to the chain the required elasticity and flexibility in different directions, as well as to keep it under tension. This clasp also serves as a securing means for the longitudinal chain *g* which is connected at one end thereto and the other end to a suitable ring fastening *f* secured to the bottom of the sole in the instep. This chain *g* and chains *e'* provide a T-shaped construction and is a more secure device than if only the lateral chains were used. Also, the chains *e'* can be shaped to form a T by making them a trifle longer and the chain *g* somewhat shorter or any other suitable shape can be adopted, but, it has been found that the arrangement as disclosed in Fig. 2 gives the best results and is more comfortable to the wearer.

If the sole of the shoe is made of a hard material, such as leather, a strip of soft material, as rubber, can be inserted between the chains and the sole, which will thus act as a shock absorber and prevent undue discomfort to the foot of the wearer.

The chains can be fastened as, for instance, shown in Fig. 4, and Fig. 3 shows the clasp in a position that it assumes before securing the chains thereon.

I claim as my invention:—

1. An anti-skid device for boots and shoes, comprising a plurality of supporting or securing members fastened to the inner sole of the shoe; and a chain adapted to be removably attached to the supporting members over the sole of the shoe.

2. An anti-skid device for boots and shoes, comprising at least two supporting or securing members fastened to the inner sole of the shoe; a cross-brace connecting the members together; and a chain adapted to be removably attached to the supporting members over the sole of the shoe.

3. An anti-skid device for boots and shoes, comprising at least two supporting or securing members fastened to the inner sole of the shoe; a cross-brace connecting the members together; and a chain adapted to be removably attached to the supporting members over the sole of the shoe by means of links, each of which is adapted to fasten one end of the chain to a supporting member.

4. An anti-skid device for boots and shoes, comprising at least two supporting or securing members fastened to the inner sole of the shoe; a cross-brace connecting the members together; a chain adapted to be removably attached to the supporting members over the sole of the shoe by means of links, each of which is adapted to fasten one end of the chain to a supporting member; and a spring for the chain to render the chain flexible.

5. An anti-skid device for boots and shoes, comprising a plurality of supporting or securing members fastened to the shoe; a ring fastening secured in the instep of the shoe; and chains removably secured to the supporting members and the ring fastening in an approximate T-shape.

6. An anti-skid device for boots and shoes, comprising a plurality of supporting or securing members fastened to the shoe; a ring fastening secured in the instep of the shoe; a cross-brace connecting the supporting members together; chains removably secured to the supporting members and the ring fastening in an approximate T-shape; and a clasp securing the stem chain of the T to the beam chains and adapted to act as a spring.

7. An anti-skid device for boots and shoes, comprising a plurality of supporting or securing members fastened to the shoe; a ring fastening secured in the instep of the shoe; a cross-brace connecting the supporting members together; chains removably secured to the supporting members and the ring fastening in an approximate T-shape; a clasp securing the stem chain of the T to the beam chains and adapted to act as a spring; and a link for each supporting member and the ring fastening whereby the chains may be removed therefrom.

In testimony whereof, I affix my signature.

JAMES M. NAHON.
